CLAIM

The ornamental design for a wireless remote control as shown and described.

DESCRIPTION

1. Wireless remote control

1.1 : Perspective

1.2 : Front

1.3 : Back

1.4 : Right

1.5 : Left

1.6: Top

1.7: Bottom

The broken lines showing portions of the wireless remote control form no part of the claimed design.

1 Claim, 7 Drawing Sheets(56)
